UNITED STATES PATENT OFFICE.

LOUIS NARCISSE PRUDHOMME, OF BERMUDA, LOUISIANA.

SADDLE-BAG.

SPECIFICATION forming part of Letters Patent No. 761,783, dated June 7, 1904.

Application filed August 8, 1901. Renewed May 6, 1904. Serial No. 206,694. (No model.)

To all whom it may concern:

Be it known that I, LOUIS NARCISSE PRUDHOMME, a citizen of the United States, residing at Bermuda, in the parish of Natchitoches and State of Louisiana, have invented certain new and useful Improvements in Saddle-Bags, of which the following is a specification.

My invention relates to saddle-bags; and its primary object is to provide a device of this character which will thoroughly protect its contents from the weather and be convenient and durable in use.

The improvement is designed especially for use in the transportation of the mails where horseback service is necessary, as in rural free delivery, &c. With this end in view I provide a bag provided at its front with two receptacles, each made up of two cylindrical sections, for the reception of rolls of paper, parcels, &c., and two rear boxes or receptacles of rectangular form for the reception of letters, circulars, &c. These receptacles are all so situated and constructed as to permit of ready access by the carrier while seated in the saddle. With these ends in view the invention consists in the particular construction, arrangement, and combination of parts hereinafter described, illustrated in the accompanying drawings, and pointed out in the appended claims.

Referring to the accompanying drawings, forming a part of this specification, Figure 1 is a top plan view of the saddle-bag spread out and disconnected from the saddle in order to show the construction and position of the various bags or compartments more clearly. Fig. 2 is a horizontal sectional view of the same, taken on line *a b* of Fig. 1.

Similar numerals of reference indicate like parts throughout both figures of the drawings.

In the drawings, 1 designates the saddle-blanket made of leather, canvas, or some other suitable and convenient material, and comprising parallel strips 2 and 3, connected by a central strip 4, which latter is formed at its rear end with a semicircular slit 5 to adapt it to fit over the rear end of the saddle. To each side of the front strip 2 there are receptacles 6, comprising two cylindrical sections, 50 closed by a semicircular cover 7, secured by

staples 8 and cords 9, secured by a padlock or other suitable fastening. To each side of the rear strip 3 there is secured a box or receptacle 10. These boxes are of rectangular form and provided with hinged covers 11, formed with slots adapted to fit over a series of staples 12, projecting from the top edges of the boxes, and to be secured by a strap or cord 13, secured at one end to the box and passed through the staples, the free end being secured by a padlock 14, or other suitable fastening. To protect the several boxes or receptacles from the weather, I provide curtains 15, secured at their upper ends to the strips 2 and 3 and adapted to be unrolled to cover the boxes or rolled up, as shown in the drawings.

16 designates openings at the front of the saddle skirt or blanket, through which the horn of the saddle projects, the plurality of such openings adapting the device to saddles of varying size.

17 designates openings for fastening the blanket proper to the saddle. These openings, as well as the openings 16, are all eyeleted to prevent the same from tearing out.

18 designates semicircular metal guards to prevent the semicircular slit 5 from tearing out at these places.

19 designates a broad strap sewed at its front end to the saddle-blanket and provided at its rear end with eyeleted openings 20 and adapted to be brought forward, forming a loop for the gun or rifle which may be desired to be carried, and then hooked over the horn of the saddle projecting through one of the openings 16.

21 designates a small roll of oil-cloth, into which may be rolled a blanket, and thus be kept dry.

22 designates buckles for fastening the lower portions of the curtains 15 to the saddle-blanket.

Having thus described my invention, what I claim, and desire to secure by Letters Patent, is--

1. A saddle-bag, consisting of a saddle-blanket comprising parallel strips of material connected by a central strip formed with a transverse slit, boxes or receptacles secured

to said strips, covers for said boxes or receptacles, means for securing said covers, curtains secured at their upper ends to the saddle-blanket, and adapted to be rolled up when not in use, substantially as described.

2. A saddle-bag, comprising a saddle skirt or blanket formed with a plurality of openings at the front end and transversely slitted, and boxes or receptacles secured to said skirt or blanket, substantially as described.

3. The combination with a saddle-blanket, comprising parallel strips of material connected by a central strip, formed with a trans-

verse slit; of boxes or receptacles secured to said strips; covers for said boxes or receptacles; means for securing said covers; and curtains secured at their upper ends to the saddle-blanket, and adapted to be rolled up when not in use, substantially as and for the purpose set forth.

In testimony whereof I have affixed my signature in presence of two witnesses.

LOUIS NARCISSE PRUDHOMME.
